UNITED STATES PATENT OFFICE.

WILLIAM A. BRADEN, OF CHICAGO, ILLINOIS.

TRACK CONSTRUCTION.

No. 927,216.

Specification of Letters Patent.

Patented July 6, 1908.

Application filed July 24, 1907, Serial No. 385,291. Renewed May 27, 1909. Serial No. 498,686.

To all whom it may concern:

Be it known that I, WILLIAM A. BRADEN, a citizen of the United States, residing at Chicago, in the county of Cook and State of Illinois, have invented certain new and useful Improvements in Track Construction, of which the following is a specification.

My invention relates to track construction, and has for its objects: to provide a stiffer track than has heretofore been possible, by the form of track now in use, and with a minimum amount of metal; to provide a track wherein a small rail section may be used; to provide a stiffening means for the track which will assist in anchoring it to the road bed and prevent washing of such road bed; to provide an improved means for supporting the rail joint, and finally, to provide a track which will not give under the impact of the engine drivers, to the end that a maximum efficiency in the motive power is secured.

Certain embodiments of the invention are illustrated in the accompanying drawing, wherein—

25 Figure 1 is a transverse section through my improved track construction along the line I—I of Figure 2;

Figure 2 is a longitudinal section through the track,

30 Figure 3 is a transverse section enlarged on the line II—II of Figure 2;

Figure 4 is an enlarged transverse section showing a modified form of securing means, and

35 Figure 5 is another transverse section showing a modified form of stiffening section and securing means.

Briefly stated, the invention comprises the ordinary track provided with the usual cross-ties, together with a stiffening means arranged longitudinally beneath each of the rails, and secured rigidly either to the ties or to the ties and rails. The invention also includes a means for supporting the rail joint 45 from the stiffening members.

Referring to the drawing, 1 are the rails, which rest upon the usual cross-ties 2, and 3 are the longitudinal stiffening members, which members are built up of angle irons placed back to back and riveted together as shown. The stiffening members 3 extend longitudinally of the rails, and are secured to the ties by means of the bolts 4, and also engage the edge of the rail as shown in Figure 1, 50 and assist in holding the rail to the ties. As shown in Figure 2, the joint 5 between the

stiffening members is made to come at a point intermediate the rail joints, whereby any weaknesses due to double joints at the same point are avoided. In order to support 60 the track rigidly at the joint the metal blocks 6 are provided, which blocks are recessed upon their upper surface as indicated in Figure 3, to receive the flanges of the rails and bear upon their lower sides upon the top of 65 the stiffening members. These blocks 6 are recessed at 7, as shown in Figure 3, in order to lighten them, but may be made in any desired shape suitable for supporting the joint.

Another form of stiffening section is shown 70 in Figure 4, the stiffening member in this modification being the T-iron 8 shown. The succeeding sections are secured to each other by means of the tie-plates 9 riveted to the ends of adjoining sections. The bolts 10 employed in this form of construction are also secured at their upper ends to the rail, in a different manner. Instead of having the heads of the bolts overlap the rails as shown 75 in Figure 1, small plates 11 are employed 80 overlapping the edges of the rail, and these plates are retained by means of the nuts on the bolts 10.

In Figure 5 still another form of stiffening section is shown, said section being the deck beam shown. A different arrangement for securing the bolts 12 to the rail is also indicated. As here illustrated, the head of the bolt lies upon the top flange of the rail, the shank of the bolt passing through the flange 90 and being secured at its lower end in the usual manner. It will be apparent that a large number of different stiffening sections might be employed, as well as a number of different means for securing the stiffening 95 sections to the ties and to the rails.

It is thought that the utility of the construction heretofore described will be obvious. A very stiff track in proportion to the material employed is secured, because of the distance by which the rail and stiffening section are separated, which gives a large amount of inertia for the track section. This increased stiffness not only renders the track 105 safer and more durable, but also gives a better driving surface for the locomotive drivers, thereby increasing the efficiency of the motive power. The stiffening sections also perform another important function; viz., the anchoring of the track to the road-bed and the preventing of any lateral displacement of the track or washing out of the 110

ballast during heavy storms. The two bolts which secure the stiffening members to the ties and rails also add additional security and prevent spreading of the rails in case of loosening of the spikes with which the rails are additionally secured to the ties. It will also be apparent that the supporting blocks 6 placed beneath the rail joint add greatly to the value of the construction, as an absolutely stiff joint is secured, which result was impossible in the old form of rail joint wherein the ends of the rails rested upon a plate upon the ties.

Having thus described my invention and illustrated its use, what I claim as new and desire to secure by Letters Patent, is the following:

1. A track comprising a rail, cross ties therebeneath, a flanged stiffening section beneath the ties parallel to the rail, and secur-

ing means for each side of the flange of the rail comprising substantially vertical bolts extending through the flange of the section the rail flange and the ties.

2. A track comprising rails, cross ties 25 therebeneath, flanged stiffening sections beneath the ties parallel to the rails, and bearing blocks between the rail joints and stiffening sections with their ends in close proximity to the ties on either side, and having 30 their upper surfaces recessed to receive the flanges of the rails.

In testimony whereof I have hereunto signed my name in the presence of two subscribing witnesses.

WILLIAM A. BRADEN.

Witnesses:

PAUL CARPENTER,
JAS. N. LORENZ.
